(57) **CLAIM**

The ornamental design for a core sample separator for marking boxed drilling core samples, as shown and described.

DESCRIPTION

FIG. 1 is a bottom view of a core sample separator for marking boxed drilling core samples.

FIG. 2 is a right view of a core sample separator for marking boxed drilling core samples.

FIG. 3 is a front view of a core sample separator for marking boxed drilling core samples.

FIG. 4 is a left view of a core sample separator for marking boxed drilling core samples.

FIG. 5 is a top view of a core sample separator for marking boxed drilling core samples.

FIG. 6 is an isometric front bottom right view of a core sample separator for marking boxed drilling core samples.

FIG. 7 is an isometric front top right view of a core sample separator for marking boxed drilling core samples.

FIG. 8 is an isometric front bottom left view of a core sample separator for marking boxed drilling core samples; and,

FIG. 9 is an isometric front top left view of a core sample separator for marking boxed drilling core samples.
